UNITED STATES PATENT OFFICE.

HENRY G. M. HOWARD, OF KALAMAZOO, MICHIGAN.

TWO-WHEELED VEHICLE.

SPECIFICATION forming part of Letters Patent No. 367,105, dated July 26, 1887.

Application filed November 2, 1886. Serial No. 217,771. (No model.)

To all whom it may concern:

Be it known that I, HENRY G. M. HOWARD, a citizen of the United States, residing at Kalamazoo, county of Kalamazoo, State of Michigan, have invented a new and useful Two-Wheeled Vehicle, of which the following is a specification.

This invention relates to that class of two-wheeled vehicles in which are employed spiral-spring hangers as a means of suspending the body or seat-bars from the thills.

The object of the invention is to produce a spiral-spring hanger so constructed and associated with the thills and body or seat-bars that the spring will be partially compressed from both ends toward its center when in its normal condition, whereby less spring-steel is required and less spring action is attained in a double-acting spring of this class, the utility of which is explained below. Other objects and the utility and construction are below set forth.

In the drawings forming a part of this specification, Figure 1 is a side elevation with one wheel removed; Fig. 2, lettered details of Fig. 1, enlarged. Fig. 3 is an elevation of the spring-hanger, enlarged from Fig. 1; Fig. 4, an elevation of the spring; Fig. 5, a detail of the hanger enlarged, parts being in vertical section; Fig. 6, a plan of one of the caps to the hanger and the end coil of the spring; and Fig. 7 is an elevation of the adjusting-hook, enlarged from Figs. 1 and 2.

Referring to the lettered parts of the drawings, B is the thill; C, the cross-bar of the thills; e, the seat-bars or body jointedly attached at the forward end to the thills; A, the wheel, and D the seat, all substantially as heretofore in this class of vehicles.

Of course the vehicle on both sides is like the side here shown. So far as the position of the suspending-hangers is concerned, they are attached pivotally or jointedly to the thills at one end and to the body at the other end at the points substantially as heretofore.

So far as I know, the spring-hangers before employed have either expanded under the weight of the rider or compressed from one end only; but I am aware that lapped bars bearing a double-acting spiral spring have been used in other relations—such, for instance, as

sustaining a vehicle-tongue; but I have especially adapted the spring-hanger here shown for its particular use in the new combination of parts, which appears in the following details of construction.

The free ends of the hair-pin-shaped rods *u* are secured to caps or cups *f*, with the loop end of the lower bar pointing downward and attached to the body *e*, and the loop end of the upper bar pointing upward and attached to the thill or cross-bar, the parallel bars of the rods *u* passed vertically and loosely through holes in the cups *f*.

The loop end of the bars *u* are swelled a little laterally, forming shoulders. The length of the bars from these shoulders to their free ends controls the length of the hanger in its normal condition, Fig. 3. The design is that the spring *a*, Fig. 4, shall be slightly compressed from each end when placing it between the cups *f*, thus making a stiffer spring with comparatively lighter steel.

Fig. 5, in which the rods *u* are broken and the cup *f* and two spirals of the spring *a* appear in section, illustrates the end of the spring in the cup, and also plainly shows the rods passing through the cup *f* and the free end of one attached thereto.

Another important object in forming stops to fix the position of the cups and employing a spring which has to be compressed to occupy the space between the cups, is that if the same spring were not compressed when in its normal condition it would yield too readily and too far when the rider mounts the seat, thus allowing the body to swing unduly downward, or else the body would be sustained unduly high above the axle, and in either case the swing of the body would be too great. This could partially be obviated by employing heavier springs; but as steel is sold by the pound, economy is a vital point in this direction to manufacturers of such vehicles. It will be observed that the stops or shoulders which the cups contact are a little removed from the loop end of the rods, and at the terminus of or near to the straight portion of the bars. Were it not for these stops, the springs by their pressure against the cups would force the latter in a wedging manner in the bow of the rods, so that the holes in the cups would

cramp against the inside of the bow part of the rod, or else the cup would contact with the hook to which the bow was hung, in either case preventing a proper and free action of 5 the parts.

When the body *c* is borne down by the weight of the rider, the rods *u* draw their respective cups *f* toward each other, thus compressing both ends of the spring alike, as above 10 stated, Fig. 2. Of course when the body rises the spring expands alike at both ends as the cups are forced apart farther by the rods, which lap past each other. Such hangers having this action of the spring *a* are desira- 15 ble in carts designed to carry either one or two persons, as the elasticity and delicacy of action are multiplied, for a light-weight person, with a spring heavy enough to sustain two persons. There is a more equal strain on 20 the spring. A shorter spring may be em- ployed, and one important feature is that less continuous length of the hanger-rods is ex- posed when the spring is compressed than there would be were the spring compressed from one 25 end only. Thus the rods are less liable to be- come bent out of shape.

At *v* is shown a double hook attached to and pendent from the thill; or, if preferred, this hook may be attached to and project up- 30 ward from the seat-bar *c*. The eye end or bow

of the rod *u* is hooked over one of the hooks. It will be observed that one of the hooks is nearer the thill than the other and on a different vertical plane. By this means the body may be raised or lowered, and the angle of 35 the hanger changed to adjust for heavy and light persons. By changing the angle of the hanger the leverage of the seat-bars on their forward fulcrums and on the springs is changed.

There are many desirable features in the 40 peculiar spring-hanger here shown which I have not set forth, and which an actual use of the cart would alone make clear, especially in driving over rough roads.

Having thus described my invention, the im- 45 provements which I claim are—

The combination of the double acting spring- 50 hangers, the seat-bars, the thills, and the adjusting-hooks, the hooks thereof being on different horizontal and vertical planes, whereby the leverage of the seat-bars on their forward fulcrum and on the springs is changed, sub- stantially as set forth.

In testimony of the foregoing I have here- 55 unto subscribed my name in presence of two witnesses.

HENRY G. M. HOWARD.
